UNITED STATES PATENT OFFICE

ULYSSES G. LEE, OF CHICAGO, ILLINOIS

WATER CLOSET

Application filed November 1, 1929. Serial No. 404,183.

My said invention relates to improvements in the flushing arrangement of water closet bowls designed more particularly for use in connection with boats where the closet is frequently located below the level of the water surrounding the boat hull, or where such level is raised temporarily above the closet by wave action, listing of the boat, etc., and the invention aims to provide a construction which will be more efficient in its flushing action, which will be capable of ready adjustment to accord with changed conditions of use, which may be readily cleaned should it become clogged, and which will be proof against flooding from backing up of water in the discharge pipe, due to superior elevation of the exterior water.

With these and other objects in view, the invention comprises the novel construction hereinafter described, that which constitutes the invention being defined by the claims appended hereto.

An embodiment of the invention is illustrated in the accompanying drawings in which:

Figure 1 is a longitudinal vertical section on line 1—1 of Fig. 2, and

Fig. 2 is a section on line 2—2 of Fig. 1.

Fig. 3 is a section on line 3—3 of Fig. 2.

Figures 4, 5 and 6 are sectional detail views of the check valve at the top of the discharge pipe.

Referring by reference characters to this drawing, the numeral 3 designates the bowl having its rim provided with the circumferential passage or conduit 3^a for the flushing water which is discharged into the bowl through the ports or openings 3^b. The bowl is formed with a horizontal base extension 3^c containing the bowl discharge passage which extension has a flat shelf-like portion on which is seated a bed portion 4 which has a passage or opening 4^a which alines with the upturned end or mouth of the bowl discharge passage. Mounted on this bed plate 4 is a discharge pipe 5 of substantially inverted U shape, the leg 5^a of which communicates with the passage 4^a in the bed plate while the other leg 5^b alines with a passage 4^b in the bed plate by which it is connected to the

sewage disposal pipe 6. The discharge pipe 5 is extended upward for a distance sufficient to ensure its upper bend being always above the level of the water outside the boat hull. The distance to which it is extended upward may, of course, be varied according to the 55 situation of the closet in the boat relative to the water line.

The passage 4^a is preferably contracted towards its top to form a valve seat provided with a suitable packing indicated at 7 to coact with a valve 8, preferably of the ball type, which is located in a ball containing chamber 5^c formed in the leg portion 5^a and communicating with the upward discharge passage therein by an outlet port 5^d of less diameter than the ball valve, whereby the latter is retained within the valve chamber. This valve prevents backing up of water in the discharge pipe due to location of the closet 70 below the water line or wave action and the like.

Check valves, however, can never be depended on against leakage in pipes used for conduction of sewage, but by reason of the 75 U-shaped bend of pipe 5 being carried well above the water line, if the valve should fail to seat for any reason, flooding of the bowl due to backing up of outside water is effectually prevented.

It will be observed that if the U-shaped pipe 5 were left full of water at the completion of a flushing operation and the check valve fail to effect a liquid tight contact with its seat, there would be danger of the said pipe 5 acting as a siphon and drawing water in a reverse direction with resultant flooding of the seat. To avoid this, I provide the said pipe 5 with a check valve 5^x located at the top of the bend and comprising a pipe section α 85 tapped into the bend of pipe 5 and having a valve chamber α' provided with a ball valve α^2 designed to permit entrance of air but exclude egress of water.

The upward discharge leg is more upwardly flaring to secure a Venturi tube effect, and a jet passage 5^y discharges water centrally into the lower end of the said leg 5^a in line with the axis thereof, with an ejector action which is strong enough to force the water and sew- 95

age upward through the discharge pipe 5 and out through pipe 6 into the outside water, and to evacuate the contents of the bowl through said pipes.

5 The bed portion 4 is formed hollow and receives water from a chamber 5^a formed on the descending leg 5^b, the lower end of which communicates by aligned ports with the hollow interior of the bed plate. Water is supplied to chamber 5^a by pipe 8^a connected to any suitable flushometer or device not shown. The jet passage 5^e is in communication with the hollow interior of the bed plate as shown at the left of Fig. 2, the water thus supplied 10 through this jet serving to start the siphon action.

The member 5 is provided with another passage or chamber 5^c which communicates at its lower end with the hollow interior or 20 water space of the bed plate 4 and at its upper end with the water chamber 3^a in the bowl rim. Said upper end is shaped to form a valve seat with which cooperates a valve 9 which may be of the ball type, provided with 25 regulating screw 10 whereby the amount of water diverted to the bowl rim may be regulated or it may be entirely cut off for cleaning purposes. The member is provided at its upper end with a clean out plug 11.

30 It will be noticed that the ball valve chamber 5^c is shaped to provide an enlarged part offset from the port leading into the lower end of the leg 5^a, the arrangement being such that when the water lifts the valve, it moves 35 to one side and allows unobstructed passage of the contents of the bowl under the flushing action.

Having thus described my invention what I claim is:

40 1. In a water closet, a bowl, a discharge passage from the bowl, a water jet for said discharge passage, and a valve between the jet and bowl.

45 2. In a water closet, a bowl, a discharge pipe connected to the bowl outlet, a water injector discharging into said discharge pipe, and a check valve interposed between the injector and bowl outlet.

50 3. In a water closet, a bowl, a discharge pipe of substantially inverted U-shape having one leg connected with the bowl, a water jet discharging upwardly into said leg, and a check valve located to one side of said jet.

55 4. In a water closet, a bowl, a discharge pipe of substantially inverted U-shape having one leg of downwardly converging form and provided with an enlarged laterally offset portion forming a valve chamber communicating with the bowl outlet, a check valve in said chamber, and a water jet discharging axially into the lower end of said leg.

60 5. In a water closet a bowl having a laterally projecting base portion forming a shelf, a hollow base block seated on said shelf and having a passage communicating with the

bowl outlet, a discharge pipe carried by said base and having a leg communicating with said passage, said leg having a jet passage aligned with the passage in the leg and means for supplying water to said hollow base.

70 6. A water closet according to claim 5 in which the discharge pipe leg has an enlarged chamber at one side of the jet and forming the communication with the bowl, and a ball valve located in said enlarged chamber.

75 7. A water closet according to claim 5 in which the bowl has a peripheral flushing conduit and a passage is provided leading from the hollow bed plate to said flushing conduit provided with a regulating valve.

80 8. In a water closet, a bowl, a discharge pipe of substantially inverted U-shape having one leg connected to the bowl, a water jet discharging upwardly into said leg, a check valve for preventing return of water into the bowl, and a check valve for admitting air to the top of the said U-shaped pipe.

85 9. In a marine water closet, a bowl located so as to be at least at times below the water line, a discharge pipe of substantially inverted U-shape having one leg connected with the bowl, said pipe having its bend located so as to be above said water line, a water jet discharging upwardly into said leg and arranged to eject water therethrough and evacuate the bowl, and a check valve arranged to admit air to said bend above the water line.

90 In testimony whereof, I affix my signature.
ULYSSES G. LEE.
